CLAIM

(22) Filed: **Aug. 29, 2007**

We claim the ornamental design for a dimmer switch, as shown and described.

Related U.S. Application Data

(62) Division of application No. 29/261,693, filed on Jun. 19, 2006.

DESCRIPTION

(51) **LOC (8) Cl.** 13-03

FIG. 1 is a perspective view of a dimmer switch according to a first embodiment of our new design.

(52) **U.S. Cl.** D13/170

FIG. 2 is a front view thereof.

(58) **Field of Classification Search** D13/162, D13/169, 170; 174/66; 200/520, 531, 536, 200/252, 293, 333, 335, 329; 338/128, 176; D8/353; 307/116, 125, 139

FIG. 3 is a left side view thereof.

See application file for complete search history.

FIG. 4 is a right side view thereof.

(56) **References Cited**

FIG. 5 is a top view thereof.

U.S. PATENT DOCUMENTS

FIG. 6 is a bottom view thereof.
